FABRIC FOLDING MACHINE

Forrest J. Couch, Cincinnati, Ohio, assignor to
 The American Laundry Machinery Company,
 Cincinnati, Ohio, a corporation of Ohio

Application February 18, 1933, Serial No. 657,407

15 Claims. (Cl. 270—62)

My invention relates to a folding machine for laundry articles such as towels, napkins, pillow cases, handkerchiefs, or the like. It also contemplates the provision of a stacking apparatus 5 for stacking the articles after they have been folded.

It is the object of my invention to provide an apparatus wherein articles such as those above mentioned may be fed into the apparatus direct from an ironing machine or otherwise and in a flat unfolded state and will then be primarily folded commensurately with their size and type, being also cross folded if desired, and finally being delivered to a stacking mechanism which 10 automatically stacks the folded articles. A further object of my invention is to provide a plurality of stacking devices for accommodating articles of different folded size, with means for selectively causing delivery of a folded article 15 from the folding means to the desired stacking apparatus.

Various other objects and advantageous features of my invention may be seen in the following description and one embodiment thereof 20 may be seen in the accompanying drawings wherein similar characters of reference designate corresponding parts, and wherein:

Fig. 1 is a side view of a folding and stacking mechanism constructed in accordance with my 25 invention; Fig. 2 is a fragmentary sectional view taken on the line 2—2 of Fig. 1 and showing the disposition of the centering means about which the articles are wound as the first step in the folding operation, and the relative position 30 of the centering means with the article conveying tapes; Fig. 3 is a view taken on the line 3—3 of Fig. 1 and showing particularly the means for removing the articles from the centering means about which they are wound and 35 delivering them to the second step of the folding operation; Fig. 4 is a view, partly in section, showing more in detail the removal of the goods from the centering means and its delivery to the cross folding means; Fig. 5 is a view taken on 40 the line 5—5 of Fig. 1 and showing details of the cross folding means; Fig. 6 is a view taken on the line 6—6 of Fig. 2 and showing the means for guiding the article around the centering means about which it is wound; Fig. 7 is a view 45 similar to Fig. 6 showing the position of the article just before being removed from the centering means and subjected to the cross folding means; Fig. 8 is a view taken on the line 8—8 of Fig. 2 and showing the article guides in full 50 inoperative position; Fig. 9 is a fragmentary plan view of the conveying and stacking apparatus for the folded articles; Fig. 10 is a view taken on the line 10—10 of Fig. 3; Fig. 11 is an enlarged detail view of the shelves provided in the 55 stacking apparatus for receiving the folded ar-

ticles; Fig. 12 is a fragmentary view showing the clutch means forming a part of the automatically operating means for the stacking apparatus, the clutch means being in disengaged position; Fig. 13 is a view similar to Fig. 12 but showing the clutch in engaged position; Fig. 14 is a detail view, partly in section, taken on the line 14—14 of Fig. 12; Fig. 15 is a diagrammatic view showing the electrical circuits forming a 10 part of the apparatus; and Fig. 16 is a view similar to Fig. 8 showing the article guides or deflectors in two different positions whereby to produce folds of different widths by first forming cylinders of different diameters.

In the drawings, I have shown a folding and stacking apparatus constructed in accordance with my invention disposed in conjunction with and adapted to receive ironed articles from the delivery tapes of an ironing machine including the usual ironing roll 1 and ironing chest 2. 15 The work folding apparatus includes a suitable frame 3 carrying a plurality of spaced narrow work conveying tapes 4 as shown in Figs. 2 and 3. The upper laps of these tapes travel from left to right as viewed in Fig. 1 around a driven roller 5 and idler rollers 6 and 7, the roller 5 being driven by a motor or power unit 8, gear reduction unit 9 and a sprocket chain 10 that passes around a sprocket 11 forming a part of the gear reduction unit 9, an idler sprocket 10' 20 and a sprocket 11' rigidly mounted on the shaft 12 that carries the roller 5. The upper lap of the sprocket chain 10 passes from left to right as viewed in Fig. 1 and the work carried by the tapes 4 is conveyed through the folding and stacking apparatus from the left end toward the 25 right end.

In accordance with my invention, the work in being folded is first changed from the flat state to a cylindrical shape of predetermined size and 30 wherein one-half ($\frac{1}{2}$) of the circumference of the cylinder of work will be equivalent to the width of one of the sides of the finished folded article. The means for changing the work from a flat state to a cylindrical shape consists of 35 rotatable drums or cylinders 14 carried by the side rails of the frame 3 above the tapes 4 as shown in Figs. 2 and 3 and having their free ends extending inwardly towards the center of the frame from opposite directions. As shown, the rotating drums or cylinders 14 are journaled in the side rails of the frame 3 and are arranged to have portions thereof extending outwardly of the frame, these outwardly extending portions carrying sheave pulleys 15 about which 40 V-belts 16 pass for driving the drums or cylinders. Such belts 16 pass around driven sprockets 17 carried by a shaft 18 journaled in the frame, the shaft 18 having a sprocket 19 rigidly mounted thereon which co-acts with the sprock- 45

et chain 10 hereinbefore mentioned and is driven thereby. Thus, a means for rotating the drums or cylinders 14 in the same direction is provided, this means being preferably of a nature to drive the drums or cylinders at a peripheral speed equal to or slightly greater than the speed of travel of the tapes 4.

The cylinders or drums 14 are adjustable along their longitudinal axes to move their free ends toward or away from the center of the frame for accommodating varying widths of work by being slidably journaled in the side rails and having the sheave pulleys 15 adjustably held upon their outwardly extending portions by means of set screws 20. Means are also provided for preserving the alignment of the sheave pulleys 15 and thereby the position of the drums or cylinders 14, this means consisting of retaining fingers 21 on the side rails of the frame 3 having hooked ends 22 in which annular flanges 22' on the sheave pulleys 15 travel. In adjusting the drums or cylinders along their longitudinal axes, the set screws 20 are first loosened which will permit the drums or cylinders to be moved longitudinally inwardly or outwardly whereupon the set screws are tightened which will fasten the sheave pulleys 15 in driving relation with the outwardly extending portions of the drums or cylinders and, at the same time, will maintain the drums or cylinders in their adjusted position.

To direct the work in a flat state from the tapes 4 upwardly and around the drums or cylinders 14 and into a cylindrical shape, a plurality of deflectors 23 are provided, these deflectors being mounted on rotatable shafts 24 that extend transversely of the frame as shown in Fig. 3 and are journaled in bearings 25 and 26. The deflectors themselves consist of a series of arms formed on the arc of a circle centering at or approximately at the centers of the drums or cylinders 14 and arranged to decrease in arcuate length from the outer ends of the drums or cylinders 14 towards the inner free ends thereof so that the shortest deflectors are located at the center of the frame as shown in Figs. 2, 3, 4, 5 and 6. By arranging the deflectors in this manner, it was found that an article could be removed from the drums or cylinders by the cross folding means hereinafter described more easily and with less tendency toward wrinkling.

Movement of the shafts 24 and swinging of the deflectors 23 into and out of deflecting position relative to the tapes 4 and drums or cylinders 14 as shown in Figs. 1, 3, 6, 7 and 8, is accomplished by rotation of a shaft 27 extending transversely of the frame 3 by means of a hand crank 28 mounted thereon. A pair of crank arms 29 are rigidly mounted on the shaft 27 and the free ends of these crank arms are connected to crank arms 30 rigidly secured to the shafts 24 by means of links 31. With this construction, rotation of the shaft 27 will result in rotation of the shafts 24 and the simultaneous and synchronous movement of the deflectors 23 into or out of deflecting position relative to the drums or cylinders 14.

In the operation of this part of the apparatus, the tapes 4 having been set in motion to deliver work in a flat state from the feed end of the frame toward the opposite end adjacent which the drums or cylinders 14 are mounted and which drums or cylinders are rotated in a contra-clockwise direction as viewed in Figs. 1, 6,

7 and 8, the crank 28 is operated to rotate the shaft 27 and the shafts 24 to swing the deflectors 23 from the inoperative position shown in Fig. 8 wherein they are beneath the upper laps of the tapes 4 into the position shown in Figs. 1, 6 and 7 wherein they are in deflecting position relative to the tapes 4 and drums or cylinders 14. Then, the work in a flat state being conveyed through the apparatus by the tapes 4 strikes the deflectors and is curved upwardly around the drums or cylinders 14 by the continuation of movement of the work and the rotation of the drums or cylinders to be finally rolled into the cylindrical shape shown by the dotted lines in Figs. 6 and 7 and the full lines in Fig. 4.

During operation of the apparatus, an inspection operator is stationed at a point approximately intermediate the front of the folding apparatus and the cross folding mechanism to observe the size and condition of each article being folded. If the article being folded is of a narrow width, the crank 28 is operated to rotate the shaft 27 and shafts 24 and swing the deflectors 23 to the proper position nearer to or farther away from the drums or cylinders 14 and produce a cylinder of the proper diameter to result in a folded article having the correct width fold when the cylinder is flattened. In the same manner, when a wide article passes through, the operator adjusts the deflectors to form a cylinder of a diameter for a proper fold of that article. Various positions of the deflectors are shown in Fig. 16. Also, when an article is observed that was not properly washed, commonly termed a wash-over in the laundry, the operator manipulates the deflector adjusting mechanism to affect lowering of the deflectors below the feed aprons which will allow the article to pass through the machine without being folded.

In order to produce a change in the cylindrical shape to which the work has previously been wound and produce a flat folded condition including a cross fold of the work, a cross fold blade 32 is provided which, at the proper predetermined time, is projected upwardly between adjacent tapes 4 to engage the cylinder of work at approximately its longitudinal center and between the free ends of the drums or cylinders 14 to pull the work off the drums or cylinders 14 and move it upwardly into the bite between suitable adjacent cross folding belts 33 and 34 through which the cylinder of work is pulled upwardly and thus reduced to a flat cross folded state.

The cross fold blade 32 is moved upwardly and downwardly in a guide member 35 carried by a supporting bracket 36 on the frame 3 by means of a cylinder and piston arrangement 37 likewise carried by the frame 3 and whose piston rod 38 is connected to the cross fold blade 32 as at 39. A suitable spring 40 is secured to the frame and to the upper end of the piston rod 38 at its opposite ends to act to return the piston and the cross fold blade 32 downwardly to their inoperative positions relatively fast when pressure is exhausted from beneath the piston in the cylinder 37.

An automatically operating control means for controlling the operation of the cross fold blade 32 by movement of the work through the apparatus, or its projection upwardly between adjacent tapes 4 to act on the work as shown in Figs. 3 and 4, is provided which consists of an

arm 41 having its free end disposed adjacent the tops of the upper laps of the tapes 4 and adapted, when raised by the passage of work therebeneath, to actuate a switch 42 and break an electrical circuit to a solenoid 43 which, on de-energization of the solenoid, will permit a fluid pressure control valve 44 to close and cut off a supply of fluid pressure through the pipe 45 to the cylinder 37, this action permitting the fluid pressure below the piston in the cylinder 37 to exhaust through a restricted port 46 that is constantly open but of considerably less size than the fluid pressure inlet to the cylinder so as not to preclude upward movement of the piston by fluid pressure from the inlet. The supply of fluid pressure to the cylinder 37 being cut off, fluid pressure beneath the piston in the cylinder 37 may exhaust through the restricted port 46, and the piston and cross folding blade 32 may lower to inoperative position. Thus, work traveling toward the drums or cylinders will cause a lowering of the cross fold blade before the work reaches a position beneath the drums or cylinders 14 to thereby have the cross fold blade in a position wherein it will not interfere with winding of the work about the drums or cylinders 14.

Movement of the work through the apparatus and winding of the work on the drums or cylinders 14 will result in the rearward or trailing edge of the work passing out from under the free end of the switch actuating arm 41, the parts being so arranged that the rear edge of the work passes out from under the switch arm 41 when the work is substantially entirely wound about the drums or cylinders 14 as shown in Fig. 7. Consequent dropping of the free end of the switch actuating arm 41 will operate the switch 42 to complete a circuit to the solenoid 43, and operation of the solenoid 43 will open the valve 44 to admit fluid pressure to the cylinder 37 whereby to raise the piston therein and the folding blade 32 in the manner shown in Fig. 3 to thereby pull the wound article from the drums 14 at substantially its longitudinal center and introduce such central portion of the work in cylindrical form to the cross fold producing belts 33 and 34 which will flatten out the cylinder of work to produce an article folded in one direction with the width of the fold equal to one-half the circumference of the cylinder of work and, at the same time, cross fold the article. Thus, a means has been provided for automatically controlling operation of the cross fold blade by passage of work through the apparatus. The cross fold blade 32 remains in its upwardly projected position until the next article passing through the apparatus moves under and raises the switch arm 41 to de-energize the solenoid 43 as hereinbefore described.

The cross folding belts 33 and 34 are carried by a supplemental frame 3a mounted on the frame 3 and are disposed immediately above the cross folding blade 32 and intermediate the free ends of the drums or cylinders 14. These belts are driven from the constantly operating sprocket chain 10 by means of a sprocket chain 47 traveling around a sprocket 47 rigidly mounted on the shaft 12, and around a sprocket carried on one free end of a shaft 48 which also carries a bevel gear 49 that meshes with a bevel gear 50 (see Figs. 1, 3 and 9). The bevel gear 50 is mounted on the shaft of a roller 51 around which the cross folding belt 33 travels and has on its opposite end a gear 52 that meshes with

a gear 52' on the shaft carrying the roller 53 about which the cross folding belt 34 travels whereby the rollers 51 and 53 will be driven in opposite directions and the adjacent surfaces of the cross folding belts 33 and 34 will travel in the same direction.

As shown in Figs. 5 and 9, the shafts of the rollers 51 and 53 have spacer links 54 loosely mounted thereon and extending upwardly and carrying rollers 55 rotatably mounted in their upper ends, the rollers 55 providing the upper rollers about which the cross folding belts 33 and 34 travel. These rollers 55 are connected together as by links 56 whereby, as shown by the full line and the dot-dash line position in Fig. 3, the uppermost ends of the cross folding belts may be simultaneously swung from right to left or vice versa to thereby deliver cross folded work in one direction or the other from the vertical center line of the apparatus. Operator-operated means consisting of a link 57 (see Fig. 3) connected at one of its ends to one of the spacer links 54 and at its opposite end to a bell crank arm 58 as at 59 is provided for swinging the upper ends of the cross fold belts in one direction or the other, the bell crank lever 58 being pivoted to the frame as at 59' and having a handle 60 thereon. As apparent, movement of the handle 60 upwardly or downwardly will swing the upper ends of the cross fold belts 33 and 34 in unison from one side to the other of the vertical center line of the frame.

As shown in Figs. 3 and 9, the cross folded articles emerging from between the cross folding belts 33 and 34 are delivered to horizontally extending conveying belts 61, one to the right and one to the left hand side of the cross fold belts, which are driven by suitable gears 62 and 63 meshing with the driven gears 52 and 52' respectively. These belts 61 deliver the folded articles to a stacking mechanism, there being a stacking mechanism for each of the belts but only one stacking mechanism being shown and hereinafter described inasmuch as the stacking mechanisms are identical. The belts 61 travel around the driven roller 64 and an idler roller 64'.

Referring to Figs. 9 and 10, a stacking mechanism is located adjacent the outermost ends of the conveyors formed by the belts which consist of an article elevating means 65 in the form of a U-shaped member straddling the belt 61 and adapted to be raised at predetermined intervals governed by the presence of a folded article within the stacking mechanism to elevate the article above the belt 61 and move it upwardly past pivotally mounted shelves 66 which present a substantially horizontally resting surface for the articles when in their downwardmost position and maintain the articles in stacked position between the side rails of the supplemental frame 45 as shown in Fig. 1.

The U-shaped article lifting member 65 is mounted on the upper end of a vertically extending rod 67 that is guided in its vertical movement in brackets 68 and 69 on the frame 3, the brackets including suitable bearings 70 and 71 respectively. Upward and downward movement or reciprocation of the rod 67 and the U-shaped article lifting member 65 is accomplished through a clutch mechanism on the constantly rotating shaft 72 which forms a part of the drive means for the drums or cylinders 14 and which selectively couples a gear 72 loosely mounted on the shaft, with a shaft to be driven 75

thereby. Such gear 72 meshes with and is adapted to drive a gear 73 carried by the frame 3 and having a crank arm 74 rigidly mounted on a shaft 75, the crank arm 74 being, in turn, connected with a link 76 that has its opposite end connected to the lower end of the rod 67 by a universal joint connection as at 77 whereby rotation of the gear 73 will produce reciprocation of the rod 67 and stacking member 65 upwardly and downwardly.

Operation of the stacking device just described is controlled by movement of the folded article by the belt 61 into registry with the stacking apparatus just described. As the article moves into registry with the stacking apparatus, the forward end thereof strikes and moves the operating arm 78 of a switch 79 that is rotatably mounted in a pair of brackets 80 carried by the supplemental frame 3a. Movement of the switch 79 by such movement of the switch actuating arm 78, in this instance contra-clockwise movement, serves to complete a circuit to energize a solenoid 81 (see Figs. 12 and 13) which, when energized, will move an arm 82 through a link 83 in a clockwise direction as viewed in these figures. The arm 82 is pivoted on a shaft 84 and includes a trigger arm 85 adapted to set or release the clutch mechanism on the shaft 18 for reciprocating the stacking member 65.

The clutch includes a disk 85' rigidly secured to the shaft 18 and having a plurality of rollers 86 circumferentially spaced on its one side surface. The spur gear 72 hereinbefore mentioned is loosely mounted on the shaft 18 and has a dog 87 pivotally mounted on its side surface as at 88 adjacent the side surface of the disk 85' carrying the rollers 86. One end of this dog 87 is adapted to be moved into contact with the rollers 86 on the disk 85' by means of a spring 89 to thereby connect the loosely mounted spur gear with the rigidly mounted disk as shown in Fig. 13 when the solenoid 81 is energized to hold the trigger arm 85 in the position shown. Reversely, when the solenoid 81 is de-energized by reason of no article striking the switch arm 78 and is in the position shown in Fig. 12, the trigger arm 85 is moved upwardly by a spring 90 to contact with one end of the dog 87 as the spur gear 72 rotates and move the dog to a position wherein one end thereof will not contact with the rollers 86 whereby the spur gear 72 is disconnected from driving relation with the disk 85'. With the mechanism in the position shown in Fig. 12, the stacking mechanism is in the unoperated position shown in Fig. 10.

Referring to Fig. 15, I have shown the circuits for the operation of the solenoids 43 and 81 to control operation of the cross folding blade 32 and the stacking member 65 respectively, wherein a line 91 leads from L2 to one contact of the switch 42, a line 93 leads from the other side of the switch 42 to the solenoid 43, and a line 94 leads from the solenoid 43 to L1, thus forming a complete circuit through the solenoid 43 when the switch 42 is in operative position. Similarly, a line 95 leads from L2 to the switch 79, a line 96 leads from the switch 79 to the solenoid 81, and a line 97 leads from the solenoid 81 to L1 to form a complete circuit for operation of the solenoid 81 when the switch 79 is in operative position. The switch mechanisms 42 and 79 are preferably of the well known mercury type.

In the operation of this apparatus, an ironed

article of flat work is delivered to the tapes 4 and carried toward the drums or cylinders 14 and the deflectors 23 by movement of the tapes, the deflectors 23 being assumed to be in the operative position shown in Figs. 1, 6 and 7. Such deflectors cause a winding of the article about the drums or cylinders and the article itself causes actuation of the cross fold blade 32 by passing out from under the operating arm 41 of the switch 42 as hereinbefore described whereupon such cross fold blade will be projected upwardly between the free ends of the drums or cylinders 14 as shown in Figs. 3 and 4 to pull the article from the drums or cylinders and feed the center thereof into the bite of the cross folding belts 33 and 34. These cross folding belts serve, in addition to cross folding the article, to flatten the cylinder and produce a longitudinal folded article. The folded article passes upwardly from between the cross folding belts and onto one of the conveyor belts 61 which carry the article to the stacking mechanism hereinbefore described and, by its own movement, sets the stacking mechanism in operation to move the article upwardly and deposit it on the shelf member 66 in such manner that each succeeding article is left as the bottom article in a stack as clearly shown in Fig. 1.

As a means for preventing operation of the cross fold blade 32 when articles are passed entirely through the apparatus without being wound about the drums or cylinders 14, as would occur if the deflectors 23 were in the inoperative position shown in Fig. 8, means have been provided for maintaining the switch operating lever 41 in a raised position similar to the position it assumes when work is passing thereunder with the deflectors in operative position as shown in Figs. 6 and 7.

Referring to Figs. 1 and 2, arms 98 and 99 having rollers 100 thereon adapted to ride on the upper side of the links 31 which form a part of the actuating mechanism for moving the deflectors 23 into and out of operative position relative to the drums or cylinders 14 are rigidly fixed to shafts 101 and 102 that are journaled in the side rails of the frame 3. The arms 103 extending outwardly from each side of the switch 42 are journaled in insulating blocks 104 of fibrous or other non-conductive material in the free ends of the shafts 101 and 102 as shown. In Fig. 8, it will be noted that when the deflectors 23 are in their inoperative position below the belts 4, the links 31 are in substantially a straight line between the shaft 24 and the shaft 27, both links being in the same position inasmuch as they operate in unison, whereby the shafts 101 and 102 have been rotated contra-clockwise which will rotate the switch member 42 to inoperative position and raise the switch operating arm 41 to such position that an article may pass thereunder without affecting the position of the switch member 42.

This feature of the invention has the advantage of permitting articles to be passed directly through the apparatus without being wound about the drums or cylinders 14 or acted upon by the cross fold blade 32. Such complete passage of the articles through the apparatus is desirable, for example, where a piece of work is noted by the operator to be unsatisfactorily laundered, he may operate the crank 28 to move the deflectors 23 to their inoperative position which will simultaneously render the control means for the operation of the cross fold blade 75

ineffective whereby the work may pass completely through the apparatus without interference.

Means have been provided into which these articles passed entirely through the apparatus may be delivered consisting of a receptacle formed by an apron 105 having one of its ends attached to a cross bar 106 and its opposite end attached to a cross bar 107. A series of cords 108 (see Fig. 2) are provided as a means for conveying the articles over a stationary frame brace member 109 and into the receptacle formed by the apron 105. It will be noted that these cords are also trained around the idler roller 6 which, of course, is rotated when the tapes 4 are moved which serves to move the cords 108 and thus deliver the articles from the tapes 4 to the container formed by the apron.

What I claim is:

1. Article folding apparatus, comprising means for winding an article into cylindrical shape, means for conveying an article in a flat state to said winding means, means for cross folding the cylinder, and means sensitive to movement of the article in a flat state for controlling operation of said cross folding means.

2. Article folding apparatus, comprising means for winding an article into cylindrical shape, means for conveying an article in a flat state to said winding means, means for cross folding the cylinder, and means sensitive to the trailing edge of the conveyed article for controlling operation of said cross folding means.

3. Article folding apparatus, comprising means for winding an article into cylindrical shape, means for conveying an article in a flat state to said winding means, means for cross folding the cylinder, means sensitive to movement of the conveyed article for controlling operation of said cross folding means, and means for flattening the cross folded cylinder.

4. Article folding apparatus, comprising means for conveying an article in a flat state, means including a plurality of rotating elements and article deflectors for winding the article into cylindrical shape, and means for removing the wound article from the winding means and producing a cross fold therein.

5. Article folding apparatus, comprising means for conveying an article in a flat state, means including a plurality of rotating elements and article deflectors for winding the article into cylindrical shape, and means for removing the wound article from the winding means and flattening it to produce a folded article.

6. Article folding apparatus, comprising a conveyor, oppositely disposed, rotatable article winding means about which an article is wound into cylindrical shape, deflectors for directing an article from said conveyor and about said winding means, and means for flattening the article cylinder.

7. Article folding apparatus, comprising a conveyor, rotatable article winding means about which an article is wound into cylindrical shape, deflectors consisting of a series of arms formed approximately on the arc of a circle centering at substantially the center of rotation of the article winding means for directing an article from said conveyor and about said winding means, and means for flattening the article cylinder.

8. Article folding apparatus, comprising a conveyor, rotatable article winding means about which an article is wound into cylindrical shape, deflectors consisting of a series of arms formed approximately on the arc of a circle centering at substantially the center of rotation of the article winding means and arranged to decrease in arcuate length from the ends of the winding means toward the longitudinal center thereof for directing an article from said conveyor and about said winding means, and means for flattening the article cylinder.

9. Article folding apparatus, comprising a conveyor, rotatable article winding means about which an article is wound into cylindrical shape including oppositely disposed drums terminating on each side of the center of said conveyor, deflectors for directing an article from said conveyor and about said winding means, and means for flattening the article cylinder.

10. Article folding apparatus, comprising a conveyor, rotatable article winding means about which an article is wound into cylindrical shape, deflectors for directing an article from said conveyor and about said winding means, means for producing a cross fold in the article cylinder, means governed by article movement for controlling operation of said cross fold means, and means for flattening the article cylinder.

11. Article folding apparatus, comprising a conveyor, rotatable article winding means about which an article is wound into cylindrical shape, deflectors for directing an article from said conveyor and about said winding means, means for producing a cross fold in the article cylinder, means governed by the position of the trailing edge of an article for controlling operation of said cross fold means, and means for flattening the article cylinder.

12. Article folding apparatus comprising a conveyor, rotatable article-winding means about which an article is wound in cylindrical shape, a deflector for directing an article from said conveyor and about said winding means, and adjusting means for moving said deflector toward and away from said article-winding means.

13. Article folding apparatus comprising article-winding means oppositely disposed on either side of a center line, a series of deflectors co-operating with said article-winding means and having progressively decreasing article-engaging surfaces toward said center line, and centrally disposed article-engaging means for moving the article off said article-winding means.

14. Article folding apparatus, comprising means for winding an article into cylindrical shape, a stacking device, and means for flattening the article cylinder to produce a folded article and for delivering the folded article, said delivering means being adjustable into and out of cooperative relation with said stacking device.

15. Article folding apparatus, comprising means for winding an article into cylindrical shape, means for cross folding the cylinder, a stacking device, and means for flattening and delivering the cross folded article cylinder, said delivering means being adjustable into and out of cooperative relation with said stacking device.
